SAFETY FLARE BURNER AND SNUFFER

Walter H. Neumeister, Sioux City, Iowa

Application July 22, 1933, Serial No. 681,751
Renewed April 27, 1935

6 Claims. (Cl. 67—55)

My invention relates to a safety flare commonly used for illuminating road obstructions, such as parked trucks and the like.

An object of my invention is to provide a flare 5 of this type which includes means for conveniently snuffing out the flame when desired.

A further object of my invention is to provide a weather proof flare.

A further object of my invention is to provide 10 means for retaining the snuffing mechanism in proper position at any point.

A further object of my invention is to provide for such construction which will allow convenient changing or filling of oil.

15 A further object of my invention is to provide means for adjusting the size of the flame in the flare.

A further object of my invention is to provide 20 a more efficient combustion means associated with the flare, and a further object of my invention is to provide all of the above mentioned constructions in a device of this character which can be manufactured at a minimum cost.

With these and other objects in view, my invention 25 consists in the construction, arrangement and combination of the various parts of my device, whereby the objects contemplated are attained, as hereinafter more fully set forth, pointed out in my claims, and illustrated in the accompanying drawing, in which:

Figure 1 is a sectional view taken medially of the burner of the flare.

Figure 2 is a slightly modified form of flare.

Figure 3 is an enlarged detail of the snuffer 35 retaining means.

Figure 4 is a further modified form.

Figure 5 is also a modified form similar to Figure 4 with the exception of the snuffer being removed.

40 Figure 6 is a sectional view of Figure 4 taken along the lines 6—6, and

Figure 7 is an enlarged detail of the arrangement shown in Figure 3.

I have represented the usual approximately 45 spherical body of the flare by means of the character 10. The body 10 includes the downwardly projecting and threaded flange 11 which receives the member 12. The member 12 includes the openings 13 for providing air for the burner and 50 also includes the portion 14 adapted to engage the threads in the flange 11.

Formed integrally with these members is the wick receiving portion 15 and the flared extension 16. It will be seen that the entire arrangement 55 of the wick holder, burner, etc. are all incorporat-

ed in one piece to render the manufacture of the same much simpler. The wick is represented conventionally by the dotted lines 17.

The snuffer which I represent by the character 18 includes the concave top 19 which projects beyond the main body of the snuffer at 20 to provide protection against driving wind and rain. The snuffer 18 also includes the rectangular openings 21. The bottom portion of the snuffer includes the flared flanges 22 which are adapted to 10 protect the opening 13 in the body 12.

The body 12 also includes the vertical slot 23 and a machine screw 24, which is threadedly engaged at 25 with the shell 18, and passes through the slot 23. With this construction, it would be 15 impossible to remove the snuffer by accident, and the lengthened slot permits movement of the snuffer upwardly or downwardly.

When the snuffer is forced downwardly, the openings 21 in most cases will overlap the top of 20 the shell 12 and will thereby permit of adjustment in the size of these openings, so that the flare flame can be regulated.

In snuffing the flame, the member 18 is forced 25 downwardly to its maximum limit and the openings 21 are then entirely closed and the flame extinguished.

Adjacent the slot 23, I provide the slightly outwardly bent flanges 25a. These flanges provide 30 means for retaining the snuffer cap 18 in any desired position by virtue of the tension exerted thereagainst.

Air is drawn through the openings 13 into the burner or shell 12 providing the necessary oxygen for combustion and the flames are thrown 35 through the openings 21. Any suitable oil can be used in the flare such as kerosene, signal oil or the like.

Figure 2 illustrates a modification having many 40 characteristics in common with Figure 1 with a few exceptions which will now be noted. In this form, the shell 12 is threadedly engaged at 26 with the member 27 which is soldered or suitably welded at 28 to the body of the flare 10. The member 27 includes the downwardly projecting integral flange 29, the horizontal flange 30 formed therewith, and the conical element 31.

The wick-holder 32 includes the downwardly 45 projecting ring flange 33 which is threadedly engaged with the flange 29. The threaded engagement at this point is made rather loose.

The flange 33 includes the small opening 34. The cone shaped element 31 is made approximately two-thirds the size of the opening 35 of the wick-holder 32. By means of this arrangement 55

ment, an additional small amount of air is drawn downwardly from the openings 13 through the loosely engaged threads, thence through the opening 34 into the chamber 36, which chamber is formed between the flange 33 and the element 31. This chamber acts as a mixing chamber for the air and gases from the oil passing around the cone shaped element 31 and through the opening 35. This mixing causes a more efficient reduction of the gas and air to the proper combustion point and provides a more efficient, cleaner, and brighter flame in the wick 17.

The snuffer cap 18 in forming usually includes small round fillets at the points 37 and the shell 12 would usually become jammed against these fillets thereby locking the burner shell 12 against the snuffer cap when the latter is forced downwardly to its maximum limit. To offset this difficulty, I provide the round edges 38 at the top of the shell 12.

The construction just described embodies features of convenient removal of the top structure of the flare since the shell 12 can be removed or the wick holder 32 can be conveniently removed for replacing the wick. The oil is poured through the cone 31.

It will be understood, of course, that the wick passes through both the cone shaped member 31 and the wick holder.

30 The flared members 22 prevent a driving wind or rain from penetrating through the openings 13.

Figure 4 illustrates a further modification in which the member 39 is screwed to the flange 11 and includes the neck 40. Formed integrally with the burner 12 are the arms 41 (see Figure 6) which terminate in the clamping members 42 which are clamped about the neck 40 by means of the screws 43 passing through the ears 44.

Figure 5 illustrates a similar form with the exception that the snuffer cap is not used therein and the burner 12 is combined integrally with the top portion 19.

It will be seen in both of these constructions that the air supply for combustion passes through the large openings 45 formed between the arms 41 and the walls of the shell. This provides a large area for drawing air through the burner.

Since seepage is usually present from the wick and since a certain amount of unburned oil will flow to the lower parts of the burner, I provide the small openings 46 (see Figures 1 and 2) to allow this excess oil to drop back into the torch body.

It will now be seen that I have provided a flare which combines features of simplicity, convenience in removal, interchangeability, and provides means for adjusting the size of the flame of the flare. It will also be seen that I have provided features which allow for snuffing of the flame when desired and for more efficient combustion of the gases in the burner itself.

It will also be seen that I have provided all of the above mentioned features in a construction which is easy of manufacture and reasonable in cost.

Some changes may be made in the construction and arrangement of the parts of my invention without departing from the real spirit and purpose of my invention, and it is my intention to cover by my claims any modified forms of structure or use mechanical equivalents, which may be reasonably included within their scope.

I claim as my invention:

1. A flare torch having an upper opening, an open end burner attached to the opening having air openings, a snuffer cap slidably engaged with 15 the burner having lateral flame openings.

2. A flare torch having an upper opening, an open end burner attached to the opening including an upwardly projecting conical member having an open end, a wick-holder inside the burner 20 adapted to overlie the conical member and form a chamber therebetween.

3. A flare torch having an upper opening, an open end burner attached to the opening including an upwardly projecting conical member having an open end, a wick-holder inside the burner 25 adapted to overlie the conical member and form a chamber therebetween, snuffer means slidably engaged with the burner.

4. A flare torch having an upper opening, an open end burner attached to the opening, snuffer means slidably engaged with the burner, including a snuffer cap having a plurality of flame emitting openings adapted to be regulated in size by means of the varying closure formed between 35 the said openings and the upper rim of the burner when the cap is adjusted vertically.

5. A flare torch having an upper opening, an open end burner attached to the opening, snuffer means slidably engaged with the burner, including a snuffer cap having a plurality of flame emitting openings adapted to be regulated in size by means of the varying closure formed between the said openings and the upper rim of the burner when the cap is adjusted vertically, means for 40 causing limited movement of the cap including a slot in the burner, stop means attached to the cap and passing therethrough.

6. A flare torch having an upper opening, an open end burner attached to the opening, snuffer 50 means slidably engaged with the burner, including a snuffer cap having a plurality of flame emitting openings adapted to be regulated in size by means of the varying closure formed between the said openings and the upper rim of the burner when the cap is adjusted vertically, means for preventing jamming between the snuffer cap and the burner comprising integral rounded extensions being formed at the top of the burner.

60
WALTER H. NEUMEISTER.
